UNITED STATES PATENT OFFICE

2,596,986

ADJUSTABLE MEANS FOR HOSPITAL TABLES

Cecil Claud Curtis, Washington, D. C.

Application June 8, 1948, Serial No. 31,679

8 Claims. (Cl. 280—41)

1

This invention relates to improvements in hospital tables intended for physicians or surgical use in examinations or operations, and whereby ailing patients may be supported in a multitude of positions called for in such examinations or operations.

The object of the invention, thus generally stated, is to provide a table of the character mentioned adapted to wide uses, in the hospital, office, or home, provided with improved means for enabling easily manipulated and safe and firm adjustments of head and foot sections of the table to various points of elevation and depression both above and below the normal horizontal plane of the table comprising said head and foot sections and an intermediate central or seat section.

Within the same or broad field of service, to which the invention is applicable, is included hair, face or other treatments or massages or the like, usually encountered in so-called "beauty parlors."

The preferred embodiment of the invention comprises a table having a bed or top of the adjustable sectional character recited combined with a main support comprising fixed pairs of oppositely disposed standards or supports pivoted at their upper ends to the seat or intermediate section of the bed or top, and in operation to occupy inclined or downwardly diverging relationship and adjustable braces adapted to extend from these standards or supports to the head and foot sections of the table top where they are pivoted to their respective sections at desirable points intermediate the ends of said sections, the lower ends of the braces having relatively free adjustable connections through a long range of adjustment lengthwise of the supports to correspondingly effect substantial changes of positions of the head and foot sections of the top above and below the normal common horizontal plane of the top both above and below the latter, as suggested.

A further object of the invention, and constituting an additional characteristic of the preferred embodiment thereof, resides in a foldable spreading and holding means for the downwardly diverging supports or standards adapted to fold in an upward direction to occupy positions generally parallel to the standards or supports when the latter are swung inwardly to occupy approximately parallel relations to the same, and parallel relations to the head and foot sections of the table, when the table is not in use and being shifted from place-to-place, or stored; and the same operatively associated with rollers or casters

2

provided at the lower or floor-engaging ends of the supports or standards in such way that the wheels or casters may be bodily adjusted, contemporaneously with the movements of the parts into the compact or folded relationship described, to maintain the rollers or casters in preferred operative position to bear anti-frictionally on the surface over which the folded table may be shifted without undue friction or angular positioning of the roller or caster structure that might tend to binding or objectionable screeching or noise.

Novel ancillary features of advantage attending details of construction will be apparent from the more specific description hereinafter contained when read in connection with the drawings forming part hereof and wherein the preferred, together with another embodiment of the invention are illustrated, both embodiments having improved roller adjustments and means for locking the supports or standards in their folded positions or rolling from place-to-place for lodgment out of the way when not in service.

Referring to the drawings:

25 Figure 1 is a side elevation of the preferred embodiment of the invention, the same being in open position with the top or bed portion all in a horizontal plane, that is, with the central or intermediate seat, and the so-called head and foot sections in the same horizontal plane, with the latter ready to be adjusted upwardly or downwardly to any relative positions found expedient or demanded by the special undergoing treatment of an ailing patient.

35 Figure 2 is a longitudinal vertical sectional view through Figure 1.

Figure 3 is a side elevation, the same as Figure 1, with the head and foot sections in one of their many adjusted positions, in this instance showing the head section of the top or bed of the table in a raised position and the foot section in a lowered position, the adjustment of these sections being through the range of movement marking a reverse of that shown, that is, with the foot section raised and the head section lowered from the plane of the seat portion and in a variety of such adjustments.

50 Figure 4 is a fragmentary vertical detail section through one of the standards or supports showing the different positions of the roller or caster mechanism affected by the changing of the position of the standard or support incident to the folding of the table.

55 Figure 5 is a side view of the table in its folded

and locked position for moving from place-to-place on the rollers or casters.

Figure 6 is an end view of the same.

Figure 7 is a transverse sectional view through the center of Figure 1.

Figure 8 is a plan view of the locking means for maintaining the supports or standards in spread position; and

Figure 9 is a vertical section therethrough.

Figure 10 is a face view of approximately half the second embodiment of the invention here made and constructed of metal, as distinguished from the preceding series of views where wood may well be employed in the make-up of the supporting framework.

Figure 11 is a horizontal sectional view on approximately the line 11—11 of Figure 10; and

Figure 12 is a longitudinal sectional view on the line 12—12 of Figure 10 through the locking means, the position of which is illustrated in Figure 10.

Figures 13, 14 and 15 are detail plan views, partly in section, of still another embodiment of the invention; and

Figures 16, 17, 18 and 19 are similar detail views illustrative of means for supporting the table irrespective of caster or wheel supports therefor.

Referring more specifically to the drawings wherein like reference characters refer to the same parts in the respective series of views, first with reference to Figures 1 to 9 inclusive, 13 represents the foot section, 14 the intermediate or seat section and 15 the head section of the table top or bed of the structure, these sections being hinged on transverse lines by hinges 16, movably uniting the sections in their upper surfaces whereby the foot and head sections may have substantial swinging movement or adjustment upwardly either above the plane of the intermediate or seat section 14, or downwardly therebelow, as permitted by the beveled or cut-away edges 17 (Figure 2). The table preferably has a sponge rubber or equivalent covering 18 over the hinged area of the top which will permit the adjustment referred to owing to the elasticity of said sponge rubber, and the remainder of the top may have any suitable padding 19, the whole being covered by a sheeting 20, capable of being stretched slightly or sufficiently not to interfere with the adjustment movement of the sections 13 and 15 downwardly relative to a normal horizontal plane.

On the under surface of the intermediate or seat section 14 is formed or secured, a block 21 for the attachment of standards or supports 22, pivoted at 23 to the block (it is to be understood that in describing the structure at one face or side of the table, the construction of the other side or face of the table is the same and the description will apply in that respect to the two series of uprights or supports 22, 22 without further mention thereof).

The lower ends of the standards or supports 22 carry anti-friction rollers or casters 25 to be later referred to. The intermediate portions 26 of the standards or supports 22 have their inner faces grooved to constitute elongated ways 27 to receive projecting end portions 28 of rods 29 carried by opposite pairs of links 30, pivoted at 31 to blocks 32 respectively fastened to the under surface of the head and foot portions 13 and 15 of the table top to support these sections of the top in whatever independent and relative positions to which they may be adjusted. The links 30 are interfitted in sections as at 33 (Fig-

ure 7) and adjustable through the medium of registering apertures and pins 34 to enable lengthening or shortening of the links as may be desired.

It will be understood that the projected ends 28, of the rods 29, may ride upwardly in the grooves or ways 27 when the top sections are raised, and over the inclined surfaces 35 of a long series of shoulders or seats 36 formed on the bottom walls 37 of the ways 27, as will be apparent, springs 38 around the pivots 31 engaging at one end on the bottom surface of the top section and at its other end 39 exerting a corresponding pressure on the outer edge of the link, indicated at 40, maintaining the ends 28 in engagement with a seat at all times when the section of the table is adjusted to set position.

A pull ring or handle 41 carried by a cable 42 is connected to the outer edge of each link 30, as at 43. These cables 42 may be of any type found expedient, but has in a portion of its length a relatively light coiled spring 44 to normally maintain the cord substantially taut and the pull handle or ring 41 thereof in normal location beneath the table top, the spring 38 is substantially stronger than the spring 44 to insure against the spring 44 tending in any way to pull the extensions 28 from their seats when they are supporting the top section.

The upward lifting movement on the section carrying the link will be all that is necessary to cause the link to ride up the successive inclined surfaces adjoining the seats 36, the action of the spring 38 alone effecting the interengagement of the extensions 28 with the appropriate seats 36 to firmly support the section of the top that carries the said links. However, in effecting the downward adjustment of said section it is necessary to manipulate the ring or pull cord 41 of the cable 42 to overcome the seating action of the link and to raise the extensions 28 away from the seats 35 to be free to pass downwardly in the ways 27 without obstruction from the said seats. The then lowering of the section on its hinge to the extent desired below the horizontal plane of the table top may be accomplished to the extent necessary when the release of the manual pull on the cable 42 will permit the spring 38 to force the link in a swinging direction, inwardly of the table, causing the ends 28 to interfit with the appropriate seats and maintain the parts in this adjusted position.

To maintain the table in any operative position, the supporting standards 22 are spread apart in the downwardly diverging relationship (Figure 2) to their maximum extent, and held in fixed position by spreader arms 45 and 46, pivoted at their outer ends 47 to the thereto adjacent lower end portions of the standards or supports 22, the inner ends of the spreader arms being pivotally united by a pin 48 so that the arms may fold upwardly between and approximately parallel with the standards when the latter are swung together on their pivots 23 in such relation as shown in Figure 5.

To help support the sectional table top, especially when under load—that is when occupied by a patient—and to a substantial extent relieve the strain on the pivots 23, the upper ends of the standards 22 are enlarged and beveled as at 49, to present substantial bearing surfaces for the seat or intermediate section 14 of the top (Figures 1 and 2); and at the opposite sides of the upper ends of the standards there are provided hook

portions 50, engaging the bottoms of slotted portions 51, in the walls of abutment members 52, on the outer faces of the blocks 21. This hook engagement, just described, further strengthens the connections between the standards or supports 49 and the top to relieve the pivots 23, as stated.

When the spreader members 45 and 46 are in aligned position, with the standards or supports 22 spread apart, and at their upper ends engaged as described, it is desirable that said spreader members be locked in position against upward folding tendency. To this end the member 45 has a slotted end portion 53, adapted to receive and cooperate with a latch 54 carried by a supporting member 55 and projecting freely through a slotted portion 56 in the spreader member 46, and adapted to be shifted longitudinally of the spreader members 45 and 46 to engage the latch at its free end in the slotted end 53 of the spreader member 55 to thus interlock and hold the members against movement. To prevent the latch from free movement a spring 57 frictionally engages the side of the member 46 and retains the same in either holding or releasing engagement therewith, correspondingly retaining the spreaders 45 and 46 in elongated or continuous formation, or freeing the same whereby to break or pivot in an upward direction.

When the spreader members 45 and 46 are released from their interlocked engagement, and the table is folded, as shown in Figure 5, the upward swinging of the spreader members 45 and 46 and corresponding drawing of the standards or supports 22 towards each other to the approximate parallel relationship depicted in said Figure 5, the casters or roller members 25, previously referred to, are kept in the upright position indicated in Figures 1 and 2 to insure freedom of folding movement of the stand without unduly tilting or possibly binding or screeching of the casters or roller-carrying member, this being accomplished by a rock arm 58, fixed to the pin 48, said arm 58 being connected by a link 59, to companion arm 60 on the caster or roller-carrying member 61. This link 59 is pivotally connected to the arms 58 and 60 and it will be seen that from this construction (note the changing positions illustrated in Figure 4) the caster or roller-carrying member is maintained in the same upright position throughout the folding movement of the spreader member 45, in this instance, during the folding movement of the arm 45 and upright or support 22, and this will be true in the instances of the other uprights, members 46 and the light roller constructions operatively associated therewith, so that when the device is entirely folded and the parts nested, so to speak, as illustrated in Figure 5, for example, the folded table may be readily shifted from place-to-place on the anti-friction rollers in truly operative relationship to the other parts of the structure and without tilting beyond the vertical plane which they occupy when operative, which might tend to interfere with freedom of movement or create friction and the referred to screeching or noise of the parts of the caster or roller constructions during the movement of the table.

The changing of the position of the caster or roller structure by the raising of the spreader arms 45 and 46 and folding towards the standards or supports 22 whereby the roller or wheel structure gradually assume a position relative to the standard or arm that carries the same resulting in a final positioning of the caster or roller structure in approximately true vertical

alignment with the standard or arm prevents the caster or roller structure from projecting towards and interfering with the opposite structure when the table is folded.

5 The structure or embodiment of the invention thus far described is preferably formed, in the basic frame structure, of suitable wood, while in the second embodiment of the invention, illustrated in Figures 10 to 12 inclusive, is preferably formed of suitable metal, primarily tubing. In this embodiment it is thought unnecessary to illustrate the entire supporting structure, because it will be readily appreciated that both ends of the table are substantially the same.

15 In Figures 10 to 12 inclusive, 62 represents the central or seat section of the top or bed or table, 63 the foot section and 64 the head section, although it is to be understood that either end section may be head or foot section of the 20 table; also where it has herein been stated that these sections are head and foot sections the terms have application to the suggested mechanical functions of the table because the foot section is intended to support the legs as well as 25 the feet of a patient and the head section, the back, as well as the head of a patient.

Connected to the seat section 62, by suitable pivot connections 65, are the standards or supports 66, of tubular steel or other metal as suggested, the same being adapted to fold into parallel relationship, as shown by the dotted lines, when not in use, or to be spread apart in downwardly diverging relationship when the table is in use, as indicated in the full lines. 30 The standards or supports 66 are open along one side to provide a slotted portion or way 67 having inclined edge wall portions 68 leading to adjoining stops 69, the latter to be engaged in any position of inclination of the top section 64 within 35 the limits provided for the purpose, and the engagement of the stop 69 in the predetermined position of the top section 64 is accomplished through a link or brace 70, pivoted at 71 to the top section and having a telescoping extension 40 72 adjustable by the binding screw 73, and a lateral extension or foot piece 74, extended into the way 67, to rest upon any of the seat portions 69 determined by the positioning of the top section 64. The brace or link 70 is normally in 45 engagement with its foot piece engaging the stop under the pressure of the spring 75 at the pivoted end of the link or brace 70 and exerting a constant downward and inward pressure on the link. To enable adjustment of the link or 50 brace upwardly along the standard or support 66 the same is, of course, normally adapted to move with an upward or lifting movement on the section 64 by the hand of the user. However, to obtain the opposite movement or adjustment of the link downwardly in the way 67, a grip or handle 76, at the outer end of the 55 cable 77, connected at 78 to the link may be pulled, the same as in the instance of the corresponding cable 42 in the embodiment of the invention illustrated in Figure 2, to raise the foot piece 74 out of engagement with the seat 69 at that time being engaged, so that the maintaining of the brace or link free to move along the way 67 well against the pressure of the spring 75 60 is effected, and simultaneously permitting the table sections 64—or corresponding sections 63—to lower to the point desired and at the inclination desired with reference to the normal horizontal plane of the table top or bed, when the 65 cable or pull member 76 may be released and the 70 cable 77 may be released and the 75

link or brace 70 again engaged with the appropriate seat 69 to maintain the table section 64 in the operative position intended.

When the embodiment of the invention just described is not in use, or open, as shown in Figure 10, the same is designed to be folded generally after the manner illustrated in Figure 5, showing the first-mentioned embodiment of the invention. For this purpose there is a pipe connection 79, bridging the standards or uprights 66, and pivoted to swing upwardly or downwardly with the connections 79 (one at each end of the machine) are spreader arms 80 pivoted at their inner ends 81, around a cross pipe 82, carrying sleeves 83 rigidly fastened to the ends of the cross rods, adapted to slide up and down vertical columns 84, rigidly fastened in place on the transverse central portion of the table top or bed 62. The sliding of the spreader arms 80 downwardly to the aligned or horizontal position shown in Figure 10 will, of course, effect the opening of the table to operative form; and correspondingly sliding the meeting or inner ends of the arms 80 upwardly on the columns 84 will cause the arms to fold upwardly as indicated by dotted lines in Figure 10 will correspondingly force the standards or supports 66 into vertical parallel relationship, as also indicated by the dotted lines.

Within the columns 84 are spring pressed stops 84a adapted to normally spring outwardly from the columns to occupy positions above the sleeves 83 when the latter are lowered and the spreader arms 80 are in horizontal or aligned position to retain the standards or supports 66 in their outward or operating position. With sufficient pressure the spring pressed stops 84a may recede to permit the sleeves 83 to pass thereover when the spreader arms 80 are forced upwardly, but the said stops are sufficiently strong to normally prevent any automatic rising and folding of the spreader arms that possibly might occur under pressure or weight exerted on the table.

The sections of the table, when folded—and the same is true of the embodiment of Figure 5—should be locked together against accidental re-spreading or separation of the standards or uprights, and to this end preferable fastening devices are illustrated in each instance, that of Figure 5 comprising a swinging latch 85, pivoted at 86 to one of the uprights or standards 22, provided with hooks 87 adapted to engage eyes 88 on the under surface of the table sections 13 and 15 when lowered, and which notches engage pins 89 on the opposite standards or supports at points between the hooks 87 and the pivots 86. When idle this latch 85 is held by spring action under the pivot 86.

The equivalent locking arrangement in Figure 12, comprises a short socket section 90 split at one end 91 and bolted to one of the standards or uprights 66, as at 92; the opposite end of the section 90 is open and hollow as at 93 to constitute a receiving socket for the head 94, of a latch pin 95 fastened at 96 to the companion pipe section 97, split at its end 98 and rigidly secured to the cross pipe 79 by bolting 99.

A spring pressed pin 100, passing through an aperture 101, in the pipe section 90, and engaging behind the head 94 of the latch pin, prevents separation and retains the table of Figure 10 in folded position until the latch is manually pulled apart incident to the spreading of the table into usable shape.

102 are the supporting casters or rollers for the

table, the same being adapted to swing and be thereby adjusted in a vertical direction upon the cross bar 103 uniting the ends of the standards or uprights 66, the casters or rollers being sleeved on this cross bar by a tube 104. Near the ends of the tube 104 are crank arms 105, connected by links 106, pivoted thereto at one end to the portion of the bar 80. The arrangement is such that, assuming the positions of the casters or rollers 102 to be that illustrated in Figure 10, an inward swinging movement of the standards or uprights 66 to the vertical dotted line position incident to the folding of the table, and the raising of the coupling between the rods 80 along the upright 84 will cause the endwise depression of the rod 80 (that illustrated in dotted lines) to push the link 106 downward correspondingly drawing on the end of the arms 105 and rocking the caster or wheel downwardly through an arcuate path to maintain the caster or wheel approximately in line with the rod 80 and effect a better rolling engagement with the floor than would be the case were the caster or wheel in a severely offset or angular position as would be the case were the caster or wheel not pivoted and adjustable, as stated.

In Figure 13 and following figures of the drawings, still other modifications or embodiments of the invention are illustrated, especially in reference to the automatic wheel or caster adjustment, and means enabling dispensing with the casters or wheels. In the elevation, Figure 13, the included supporting structure fragmentarily illustrated comprises the supporting standards or supports 107, corresponding to the standards or uprights 66 of Figure 10 and 22 of Figure 1, connected at the forward end by a transverse member 108, adapted to rotate as will appear, the opposite parallel standards 107 being tied together by a cross bar 109, rigidly passing through the standards 107 to prevent any separation of the standards 107 transversely of the apparatus.

Intermediate the ends of the shaft 109 is a sleeve 110 capable of turning on the said shaft, the said sleeve carrying at its opposite ends on the undersides of the standards 107 crank arms 111, the outer ends of which have a loose slot and pin connection 112 with the end of a companion crank arm 113 fast with a sleeve 114 rigidly connected at 115 to the near end of the rotatable tube 108 carried by the extreme outer ends of the standards or supports 107.

It is intended that the swinging of the under-frame, comprising the standards or supports 107, ties 109, and the bar or tube 108, towards the vertical position, directly below the table top (see dotted lines in the instance of Figure 10) shall effect a gradual and corresponding turning of the caster or wheel support 115 integral with the bushing 114 to maintain the caster support in vertical position or alignment with its standard 107 when in central or storing state, to facilitate rolling of the nested or collapsed table from place-to-place over the floor or similar surface as might be interfered with should severe angular relation of the spread standards or legs, and their casters or wheels, be maintained throughout the inward folding of the underframe including the standards or uprights 107.

10 In mounting the cross tubing or rod 108, and the connected bushings 114 for rotative support at the ends of the standards or supports 107, the latter are provided with hollow couplings 116 in which the ends 117 of cross tubing 118 fit and constitute bearing for the outside tubular mem-

ber 108 and bushings 114. In lieu of this arrangement, however, the tube or rod 119—the equivalent of the cross tube 108 just previously described—may be passed through the supporting end caster or wheel carrying member 120, the same being fixed for adjusting movement with the crank arm 121 cooperating with the companion crank arm 122 like the connection between the arms 111 and 113 of the previously described figures.

In this instance the standard or support, one at each side of the underframe are represented at 123, the cross tie therefor at 124 and caster or wheel support at 125.

A pair of instrumentalities are provided for assurance in stopping the angular positioning or adjustment of the casters or wheels in their movements with the standards 123 or their equivalent. These instrumentalities comprising first the limitations afforded by the adjustment of the pin and slot engagements 112 and additionally by the slot and pin engagements 126, the pin being carried by the shaft 119 and the slot 127 being formed in the coupling member 128 at the end of the standard or support 123.

In instances when it is desired to support the table in a relatively immovable state, that is devoid of roller or caster bearings on the floor, this may be accomplished by introducing into and adjusting lengthwise of the standards or supports 123, non-rotatable or friction feet 129 provided with stems 130 and spring latches 131 engaging through the wall of the standards or supports with cooperating shoulders or stops formed in the stems 130.

When the table of either form illustrated is folded into nested or closed position, that is, when in inoperative state when the table is not in use, means have been referred to for holding the standards in the folded or parallel relationship, notably the means 85, illustrated in Figure 5.

I claim:

1. A table of the character described comprising top sections hinged together for movement upwardly or downwardly relative to a common horizontal plane, a relatively immovable section between said top sections, standards pivoted at their upper ends to the relatively immovable section adapted to swing outwardly and downwardly beneath the relatively movable sections, braces hinged to the underside of the movable sections adapted to depend to the standards, and means for adjusting the braces in any of a number of positions on the standards to correspondingly fix the positions of the movable sections with reference to said immovable section, in combination with rollers at the lower ends of the standards, and connections movably related to said rollers and to the standards to effect up-righting of the rollers in keeping with the inward swinging of the standards from their inclined positions, said last-mentioned means being mounted and arranged to present the roller supports in approximately vertical position at an angle to the standards when the latter are in their inclined positions and in approximately vertical alignment with the standards when in their folded positions.

2. A table of the character described comprising top sections hinged together for movement upwardly or downwardly relative to a common horizontal plane, a relatively immovable section between said top sections, standards pivoted at their upper ends to the relatively immovable

section adapted to swing outwardly and downwardly beneath the relatively movable sections, braces hinged to the underside of the movable sections adapted to depend to the standards, and means for adjusting the braces in any of a number of positions on the standards to correspondingly fix the positions of the movable sections with reference to said immovable section, in combination with rollers at the lower ends of the standards, and connections movably related to said rollers and to the standards to effect up-righting of the rollers in keeping with the inward swinging of the standards from their inclined positions, said last-mentioned means being mounted and arranged to present the roller supports in approximately vertical positions at an angle to the standards when the latter are in their inclined positions, and in approximately vertical alignment with the standards when in their folded positions and including rods suspended by and depending from the relatively immovable section of the top, and horizontal connections adapted to slide upon said rods and pivotally supported at their outer end portions to the inclined standards and connected at their ends to the roller supports.

3. A table of the character described comprising top sections one of which is hinged relative to the other for movement upwardly and downwardly relative to a common horizontal plane, standards pivoted at their upper ends to a relatively immovable section adapted to swing outwardly and downwardly beneath the relatively movable section, a brace hinged to the underside of the movable section adapted to depend to the standards, means for adjusting the brace in any of a number of positions on the standards to correspondingly fix the positions of the movable section with reference to said immovable section, in combination with rods suspended by and depending from the relatively immovable section of the top, and horizontal connections adapted to slide upon said rods and pivotally supported at their outer end portions on the standards, adjustable rollers for the standards and connections between said rollers and said horizontal connections.

4. A table of the character described comprising top, middle and end sections hinged together for movement upwardly or downwardly relative to a common horizontal plane, standards pivoted at their upper ends to the middle section adapted to swing outwardly and downwardly beneath the relatively movable sections and braces hinged to the underside of the movable sections adapted to depend to the standards, means for adjusting the braces in any of a number of positions on the standards to correspondingly fix the positions of the movable sections with reference to said immovable section, in combination with rods suspended by and depending from the relatively immovable section of the top, and horizontal connections adapted to slide upon said rods and pivotally supported at their outer end portions on the standards, adjustable rollers for the standards and connections between said rollers and said horizontal connections.

5. In combination with a table having a middle section and extensions pivoted thereto adapted to be adjusted to various positions above or below a common horizontal plane of the sections, of a pair of downwardly and outwardly oppositely inclining supporting standards pivoted to the middle section and disposed beneath the end sections, braces between the end sections and the

11

standards adjustably fitting the latter, and spreading means for holding the standards in their spaced operating position, the spreading means comprising aligned oppositely disposed members pivotally connected together at their inner ends and at their outer ends pivoted to the standards, in combination with roller supports at the ends of the standards each having a toggle connection to the outer end of one of the spreader members to effect uprightness of the rollers in keeping with the inward swinging of the standards from their inclined positions.

6. A table of the character described having a top, standards pivoted to swing beneath the same, a cross bar connecting the standards together against separation, offset arms on said bar, and pivoted wheel supports having crank arms pivotally connected to said offset arms whereby to adjust the wheel support in keeping with the inward swinging movement of the standard.

7. A table of the character described having a top, standards pivoted to swing beneath the same, a cross bar connecting the standards together against separation, offset arms on said bar, pivoted wheel supports having crank arms pivotally connected to said offset arms whereby to adjust the wheel support in keeping with the inward swinging movement of the standards, and means for limiting the swinging movement of the pivoted wheel supports including a cooperating pin and slot connection.

12

8. In combination with a table of the character described, standards pivoted thereto to occupy spread apart or close folded relation corresponding to the operating or inoperating state of the table, wheel supports on the standards, and foot members telescopically associated with the standards for retaining the table against roll-on the wheel supports, the top sections of the table being pivoted to occupy positions parallel to the standards when in folded condition, in combination with spring clips on the top sections arranged to embrace the standards whereby the sections may be clasped to the standards when in the folded condition of the table.
